UNITED STATES PATENT OFFICE

147,806

DESIGN FOR A WORKTABLE

Lee L. Nieman, Chicago, Ill.

Application July 13, 1946, Serial No. 131,557

Term of patent 7 years

(Cl. D33—14)

To all whom it may concern:

Be it known that I, Lee L. Nieman, a citizen of the United States, residing at Chicago, in the county of Cook and State of Illinois, have invented a new, original, and ornamental Design for a Worktable, of which the following is a specification, reference being had to the accompanying drawing, forming part thereof.

Fig. 1 is a perspective view of a worktable, showing my new design.

Fig. 2 is a side elevational view of same.

I claim:

The ornamental design for a worktable, substantially as shown.

LEE L. NIEMAN.
